UNITED STATES PATENT OFFICE.

HENRY HIGGIN, OF NEWPORT, KENTUCKY, ASSIGNOR TO THE HIGGIN MANUFACTURING COMPANY, OF NEWPORT, KENTUCKY, A CORPORATION OF WEST VIRGINIA.

PROCESS OF MAKING BRACE-IRONS OR STRENGTHENING-IRONS FOR PERCHES AND FOR ANALOGOUS ARTICLES.

No. 874,506.

Specification of Letters Patent.

Patented Dec. 24, 1907.

Application filed February 23, 1906. Serial No. 302,638.

To all whom it may concern:

Be it known that I, HENRY HIGGIN, a citizen of the United States, and a resident of the city of Newport, in the county of Campbell and State of Kentucky, have invented certain new and useful Improvements in the Process of Making Brace-Irons or Strengthening-Irons for Perches and for Analogous Articles, of which the following is a specification.

The brace irons are primarily designed for use in connection with the wooden perch pieces of the running gear of a road vehicle, especially of road vehicles of light weight. 15 These brace irons are useful for many purposes. Among these may be mentioned their combination with wooden perch pieces, for the purpose of strengthening the latter. My mode of making this bracing iron is new 20 and useful and is an improved mode over the modes of making similar analogous shapes of metal.

The several features of my invention and the various advantages resulting from their 25 use conjointly or otherwise will be apparent from the following description and claims.

In the accompanying drawings making a part of this application, and in which similar letters of reference indicate corresponding 30 parts,—Figure 1 is an end view of the metal blank out of which the brace iron is formed. Fig. 2 is a view in perspective of this blank. Fig. 3 is a view of the end of this metal blank, as formed during the first operation of the 35 process of transforming this blank into the brace iron, and showing in vertical transverse section the rolls for doing this work, the rolls being located in conjunction with the iron. Fig. 4 is a view in perspective of the metal blank shaped in the process illustrated in Fig. 3. Fig. 5 shows in elevation the end of the metal blank when shaped according to the second operation of this process, and, also, in section, the rolls employed 40 to effectuate this operation. Fig. 6 is a perspective view of the metal bank, of which an end view is shown in the preceding figure. Fig. 7 shows in elevation the end of the metal blank when shaped according to the third 45 operation of this process, and, in section, shows the rolls employed to effectuate this operation. Fig. 8 is a perspective view of

the metal blank, of which an end view is shown in the preceding figure. Fig. 9 is an elevation of the metal blank after being subjected to a fourth operation, and also shows in section the rolls which accomplish the reduction of the metal to the shape shown in this figure. This final operation completes the metal brace or "brace iron" as it is commonly termed. The correct shape of the end of the finished brace is therefore shown in this figure. Fig. 10 is a view in perspective of the completed brace. Fig. 11 is a view showing the manner in which the 55 wooden perch piece is to be prepared to be in readiness for combination with the "brace iron". Fig. 12 shows in perspective the combination of the brace iron with the wooden perch piece. Fig. 13 shows a metal 60 blank in the process of formation into a "brace iron".

I will now proceed to describe my invention in detail. The completed channel piece to wit: the brace iron has a back A, 75 sides C, C, and flanges B, B. Each side C, on the edge opposite where it joins the back A, has one of these flanges B. The flanges B, B extend from the sides C, C, toward each other, and preferably the planes of the sides 80 of these flanges B, B are parallel to the plane of the surface of the back A. The "brace iron" may be made of any suitable metal. Iron is the preferred kind of metal.

Wherever the word "brace-iron" is employed, the word iron is to be understood to stand for and to include any metal, used in said brace.

The improved mode whereby I produce this brace-iron is as follows: The metal blank Z is a flat sheet piece of metal of the requisite size. This blank is now subjected to a top roll G, and a lower roll H having the side flanges I, I. By this operation, the blank assumes the shape shown in Figs. 3 90 and 4. The blank thus formed is now subjected to the action of a lower roll K, having side flanges L, L, and at the same time to the action of an upper or top roll J. The bottom of the upper roll is concave in cross section substantially as shown; see the concave curve JX of this roll, Fig. 5. The sides J², J² of this roll are inclined outwardly from the bottom to the point where the flanges B, B 95 100

of the iron respectively come near to or against them. The bottom portion of the lower roll K is substantially of the same convexity as is the concavity of the upper roll J; see the curve XX of this roll. The lower roll K has sides or side flanges L, L, inclined from the bottom outwardly. The combined effect of these rolls is to produce an iron having the bottom A curved inwardly and upwardly, 10 toward the midlength line of the bottom, as indicated by the curve D. The sides C, C, are inclined upwardly and outwardly, and the flanges B, B, upwardly and inwardly, as represented in Figs. 7 and 8. The rolls keep 15 the sides C, C, of the blank much inclined outwardly, and form the lower corners C^2 , C^2 of an obtuse angle shape. That is to say, these corners are not yet formed into sharp corners. Here the junctions between the 20 sides and the back are not sharp angles but gradual curves, and the back is curved up between the sides. The blank thus formed is now subjected to a top roll M and to a lower roll P. The roll M has the inclined 25 sides N and a concave bottom MX. The lower roll P has the inclined side flanges Q, Q, and the tread of this roll is convex as indicated by the curve PX. The inclinations of the working sides N, N, of the roll M 30 and the sides Q, Q, of the roll P are less than those of the rolls J and K aforesaid, that is to say, these sides of the rolls M and P are more vertical than those of the rolls J and K. The blank resulting from the operation of 35 these rolls M and P is seen in Figs. 7 and 8. In this blank, the corners at C^2 , C^2 , are made sharp, namely: acutely angulated. The iron is now in an unusually good form to receive the final operation whereby it is bent 40 to its final, complete and perfect shape. The iron is now subjected to the action of the rolls R and T. The upper roll R has a flat tread RX, and its sides S, S, are substantially vertical as shown. The lower roll T 45 is flat on the bottom tread TX, and sides or flanges V, V, of this roll are vertical. The effect of these rolls is to accomplish in a very simple manner the shaping of the iron into the completed form. This completed form 50 is illustrated in Figs. 9 and 10.

The object in having the two sets of rolls, namely: those shown in Fig. 5, and those shown in Fig. 7, both similar except that the sides of the one in Fig. 5 lie more nearly horizontal than those of Fig. 7, is to enable heavy (thick) plate to be rolled without breaking at the corners C^2 , C^2 . This gradual bending of the metal and its gradual assumption of a sharp angle at the bends which 55 constitute the corners enables the heavy metal to be successfully bent at these lines. When the metal of the blank is light (thin), it can be bent without the aid of the rolls of Fig. 5. In other words, this step of the process can

be dispensed with. In such a case, the metal 65 blank formed between the rolls G, H, of Fig. 3, can be next subjected to the rolls M, P, of Fig. 7, and thereafter to the rolls R, T, of Fig. 9. This method of forming the brace iron enables it to be manufactured in a simple, effective and economical manner. Therefore the brace iron can be made of tougher and better iron than when cast of malleable iron. Other advantages of this process will 70 be obvious and apparent.

The rolls have been described where the bottom or back of the brace iron is underneath, but the position of the rolls and the iron might be changed. This is immaterial, 75 so long as they all occupy the same position relatively to each other.

Each flange of the rolls may constitute an independent roll, but such division would be expensive, and not improve the product, to wit: the iron brace. Therefore such division is undesirable and departs to this extent from the simplicity of these features of my invention.

In Fig. 13, I have illustrated the four steps aforescribed of the process of making the 90 brace iron. The metal blank Z is seen at the left before entering the rolls. Part 1 shows the result of the first set of rolls; part 2, of the second set of rolls; part 3 of the third set of rolls, and part 4 of the fourth step of 95 rolls.

When the metal blank is a long one and the sets of rolls are successively near each other, they will all act in close succession on the blanks illustrated in said figure.

In the opening portion of this specification, I have said that these brace irons are primarily designed for use in connection with the wooden perch pieces of the running gear of a road vehicle, but I wish it understood 105 that I am aware that the brace iron is usefully applicable in many constructions other than vehicle perches, and I therefore claim my invention and its several features in their application for and in all such application. When combined with perch pieces E, 110 channels F are cut in sides of these pieces, one channel at each side, and the brace is applied to the perch, each of the flanges B, B respectively entering the adjacent channel 115 F, as illustrated in Fig. 12.

What I claim as new, and of my invention and desire to secure by Letters Patent, is:

1. The herein described process, which consists in forming flanges upon the sides of a blank, bending up the sides of the blank; upwardly curving the bottom of the blank, and finally straightening the bottom of the blank and thereby forcing the sides into a substantially vertical position, substantially as described.

2. The herein described process, which consists in forming flanges upon the sides of

a rectangular metal blank, bending the blank after said flanges have been formed so that it has inclined sides, upwardly curving the bottom of the blank, and straightening

5 the bottom thereof, thereby bringing said flanges into a substantially horizontal position and bringing said inclined sides into a sub-

stantially vertical position, substantially as described.

HENRY HIGGIN.
